UNITED STATES PATENT OFFICE.

FRANK W. PERRY, OF PHILADELPHIA, PENNSYLVANIA, ASSIGNOR TO THE HERO FRUIT JAR COMPANY, OF SAME PLACE.

DESIGN FOR A BOTTLE-CAP.

SPECIFICATION forming part of Design No. 20,300, dated November 11, 1890.

Application filed October 20, 1890. Serial No. 368,747. Term of patent 7 years.

To all whom it may concern:

Be it known that I, FRANK W. PERRY, a citizen of the United States, and a resident of Philadelphia, Pennsylvania, have invented a new and original Design for a Cap or Stopper for Bottles, of which the following is a specification.

My design is fully shown in the accompanying drawing, which represents a side view 10 of the cap or stopper.

The main portion A of the cap is cylindrical and has upper and lower milled or roughened bands or ribs a.

The cap is surmounted by a representation 15 of an acorn B, the cup b of which is milled or

roughened, and that portion d of the crown of the cap which surrounds the cup of the acorn is slightly beveled.

I claim—

The design for a cap or stopper for bottles, 20 substantially as described, and as shown in the accompanying drawing.

In testimony whereof I have signed my name to this specification in the presence of two subscribing witnesses.

FRANK W. PERRY.
